UNITED STATES PATENT OFFICE.

AUGUST SCHEMMEL, OF MILWAUKEE, WISCONSIN.

PACKAGE FOR CONFECTIONS, &c.

SPECIFICATION forming part of Letters Patent No. 355,721, dated January 11, 1887.

Application filed September 24, 1886. Serial No. 214,478. (No model.)

To all whom it may concern:

Be it known that I, AUGUST SCHEMMEL, a citizen of the United States, residing at Milwaukee, in the county of Milwaukee and State 5 of Wisconsin, have invented certain new and useful Improvements in Packages for Confections, &c., of which the following is a description.

My invention relates to packages for confections, &c.; and it consists in certain peculiarities of construction and combination of parts, as will be hereinafter described with reference to the accompanying drawings, and subsequently claimed.

15 In the drawings, Figure 1 represents a double sheet of music-paper having musical characters thereon; Fig. 2, a single sheet of such paper provided with a shield of plain paper or other suitable material; Fig. 3, a vertical 20 transverse section of my package; Fig. 4, a detail perspective view of two caps united by an elastic strip or cord; Fig. 5, a detail top view of one of the caps, and Fig. 6 a side view of my package when complete and in use.

25 Referring by letter to the drawings, A represents a tube, that is formed in any convenient manner of suitable material and of such dimensions as may be most desirable; but I prefer to make the same by simply rolling up a 30 sheet of music, chromo, print, engraving, or other attractive article capable of such manipulation. The tube A is provided with a suitable handle, B, that is preferably a piece of ribbon, fancy tape, or cord having the extremities thereof drawn around said tube at 35 or near each end of the latter and knotted, a sufficient amount of the material being left between the knots to form a grip, as shown by Fig. 6. The ends of the tube A are intended to be closed by caps C C, and these 40 caps are connected by means of an elastic strip or cord, D, as shown in detail, Fig. 4. As a matter of economy and convenience, I prefer to make the caps C C of pasteboard and ornament the same in any suitable manner.

45 The elastic strip or cord D is preferably one continuous piece passed through suitable perforations or apertures, a, in the caps and over the outer faces of the latter. In order to conceal that portion of the elastic strip or cord that comes outside the caps, I cover the same

with disks b, of paper or other suitable material, and these disks may be either plain or ornamental, as found most desirable. When a double sheet of music is employed to form 55 the tube A, the back of this sheet will come inside, and hence the confections or other substances that may be in the package cannot soil the face of said sheet or obscure the characters thereon. Where a single sheet is employed 60 for making the tube, I prefer to provide the face thereof with a shield of plain paper, c, or other suitable material, as shown in Fig. 2, in order to prevent said face from becoming gummed up or otherwise soiled with the confections or other substances inclosed by said 65 tube. The shield c would also be employed when making the tube from a chromo, print, or engraving.

In making the tube from a sheet of plain 70 paper, or one having a composition of music or picture thereon, I stretch the elastic strip or cord D so as to bring the same on the uppermost side of the sheet and the caps C against the ends. I then roll up the sheet in 75 the form of a tube and secure the ends inside the flanges d of said caps. The ribbon, tape, or cord B is now secured to the tube, and the package is ready for use. To fill the package, one of the caps is held away from an end 80 of the tube and the confections or other substances poured in, and upon the release of said cap the contraction of the elastic strip or cord will draw it down to its normal position.

85 My invention, being principally designed for confectioners, is intended to be made in lots, to supply the trade with a neat, convenient, and attractive device for doing up candies, &c.

As above stated, I prefer to employ a sheet of music for making the tube that forms the 90 main portion of my device, the object being to present each customer that buys a certain amount of confections or other substances with a musical composition, which at the same time forms the wrapper for the purchase.

If found desirable, either or both sides of the sheet that forms the tube may be embellished with printing and cuts of an advertising nature, and in case a sheet having a musical composition thereon is employed the title 95 100 should appear upon the outside in tasteful letters.

Having now fully described my invention, what I claim as new, and desire to secure by Letters Patent, is—

1. The combination, with a suitable tube, of two end caps united by an elastic strip or cord, substantially as and for the purpose set forth.
2. The combination, with a suitable tube, of two end caps united by an elastic strip or cord, and a handle suitably secured to said tube, substantially as and for the purpose set forth.
3. A sheet of music rolled up in the form of a tube, in combination with two end caps united by an elastic strip or cord, substantially as and for the purpose set forth.
4. A sheet of paper having a musical composition or other subject on one side thereof and rolled up in the form of a tube, with the printed side turned in, in combination with a shield of plain paper or other suitable material

laid upon the printed side of the sheet, and two end caps united by an elastic strip or cord, substantially as and for the purpose set forth.

5. The combination of a suitable tube with two end caps united by an elastic strip or cord, and a handle consisting of a ribbon, tape, or cord having its extremities drawn around said tube at or near the ends thereof and knotted in such a manner as to leave sufficient material to form a grip, substantially as and for the purpose set forth.

In testimony that I claim the foregoing I have hereunto set my hand, at Milwaukee, in the county of Milwaukee and State of Wisconsin, in the presence of two witnesses.

AUGUST SCHEMMEL.
